KNIFE OR SIMILAR ARTICLE

Erik Herlow, Toldbodgade 77, Copenhagen, Denmark, and Anker Christian Norgaard, Margrethevej 28, Hellerup, Denmark

Filed Nov. 12, 1964, Ser. No. 82,561

Term of patent 14 years

(Cl. D22—3)

FIG. 1 is a front elevational view of a knife showing our new design, the side opposite being similar;

FIG. 2 is an edge elevational view thereof taken from the right of FIG. 1, the side opposite being similar;

FIGS. 3 and 4 are sectional views on an enlarged scale taken on the lines 3—3 and 4—4 respectively of FIG. 2.

The stippling on the handle indicates contour and contrast between the metallic head and the nonmetallic handle.

We claim:

The ornamental design for a knife or similar article, as shown and described.
